UNITED STATES PATENT OFFICE.

EBENEZER D. HARRIS, OF LANDER, WYOMING.

MECHANICAL MOVEMENT.

Application filed May 10, 1927. Serial No. 190,252.

The present invention relates to what is believed to be a meritorious and novel mechanical movement, especially constructed for converting rotary motion from a shaft, 5 receiving its power from any source, into reciprocatory motion for actuating a pitman to be utilized for operating a suitable type of machinery.

My principal aim is to generally improve 10 upon structures of this class, by providing one which is characterized by exclusive and distinguishing mechanical features organized in such a way as to insure smooth and efficient operation, and to otherwise obtain 15 heretofore unequalled achievements in a device of this kind.

Although the invention has been constructed with a view toward providing a new principle of leverage between a wind 20 motor (windmill), and a fluid pump, I prefer to illustrate and describe it as a new form of mechanical movement capable of efficient transmission of power from any appropriate source, to machinery of any kind.

25 The details, as well as their relative association and arrangement, and the advantages derived from the new organization thereof, will become more readily apparent from the following description and drawings.

30 In the drawings wherein like reference characters are employed to designate like parts throughout the same:—

Figure 1 is a front elevational view of the complete mechanical movement as constructed in accordance with the present invention.

Fig. 2 is a side or edge view of the same, disclosing the relative planes of the respective parts.

40 Fig. 3 is a view based upon Fig. 1, and showing the position of parts at a starting point.

Fig. 4 is a similar view showing the position of parts at an intermediate point, and

45 Fig. 5 is a similar view showing the relative position of parts at the finish.

Briefly described, the improved mechanical movement comprises a stationary fulcrum and a relatively fixed rotary power 50 supply shaft located in a horizontal plane and in spaced parallelism beneath the fulcrum. A pendulous body is mounted for oscillation on the fulcrum, and swings in a direction from right to left from a starting 55 position shown in Fig. 3, to a finishing position shown in Figs. 5 and 1 respectively. A

positive driving connection, preferably gearing, is disposed between the power shaft and the body, and is constructed to move the body slowly and positively from the starting point toward the finish, and to then permit a smooth but rapid return to the starting point.

Referring now to the drawing in detail, and employing the same reference characters 65 to designate the same parts throughout, it will be seen that the reference character 6 designates a stationary fulcrum for an oscillatory lever 7. While this lever may be of some other configuration, it preferably 70 comprises a pendulous body, 8 in the form of a substantially flat segmental plate. This plate is, obviously, mounted for oscillation about the fulcrum point 6 and, as before stated, it is swingable in a direction from 75 right to left from the position shown in Fig. 3, (the starting point), toward and to the completing or finishing position shown in Figs. 5 and 1.

This plate embodies a relatively thick 80 solid portion which is provided in its back with clearance pockets 9 and 10 located on opposite sides of the fulcrum and serving a purpose to be hereinafter described. It also includes an arcuate toothed rack 11 located 85 on one marginal side and defining a peculiarly shaped opening 12. Formed on the inner edge of this opening 12, opposed to the rack teeth and arranged on an outwardly spaced plane to these teeth, we find a single pair of gear teeth 13 which function in a manner to be later described. Also, the end 90 edges of this opening 12, which are of peculiar formation, will be described later, in that they serve in promoting the advantage- 95 ous lever principle desired.

While considering this plate however, it is thought appropriate to direct attention to an outstanding eccentrically disposed pin or lug 14 with which the reciprocatory element 100 15 is pivotally connected. In this instance, the reciprocatory element is a pitman rod and is shown in dotted lines.

Attention is now invited to the power supply shaft 16 which is, of course, mounted 105 in appropriate bearings (not shown) which, in the present instance is disposed in spaced parallelism beneath the fulcrum shaft 6, (see Figs. 1 and 2). The end of this power shaft 16 terminates in a plane with the front 110 surface of the thickened portion of the pendulous body 7. This end of the shaft car-

ries a toothed gear segment 17, the teeth of which are located to mesh with the teeth of the rack 11, and thus, this gear segment is movable in a peculiarly shaped space or opening 12.

Moreover, it is fixedly mounted on the shaft 16 and turns throughout a complete revolution. Superimposed upon the central portion of this gear segment 17 and preferably formed integral therewith, is a gear sector 18. Incidentally, this gear sector is provided with three teeth which are located in a plane and in mesh with the aforesaid pair of teeth 13, on the plate 8 adjacent the fulcrum 6. It will be noted too, that the extremity of the teeth on the sector 18 are spaced inwardly of extremities of the teeth on the gear segment 17.

I would also call attention to a pair of peculiarly shaped lugs 19 and 20 which form a part of this gear sector. At this time it might be stated that the aforesaid pockets 9 and 10 are, obviously, to accommodate the rotary movement of the segmental gear 17.

By directing attention now to Fig. 2, it will be observed that the plate 8 is provided on the left or rear side with an integrally formed hub 21 carrying a radiating arm 22 terminating in a raised ovate cam 23. In addition, a similar hub 24 is keyed upon a power shaft 16 and is provided with a radiating arm 25 located in close proximity to the plate 8 and carrying a freely rotatable anti-friction roller 26 for cooperation with the cam 23. The arms 22 and 25, together with the cam 23 and the roller 26 are both formed in what may be generally designated as a retention device.

In considering the operation of this improved mechanical movement, it is to be assumed that the pendulous body 7 oscillates back and forth about the fulcrum 6. For convenience of illustration, it is to be further assumed that the position shown in Fig. 3 is a starting point for the upstroke of the pitman rod 15. It might also be considered as the finish or the return stroke of the same rod.

At this time, the teeth on the gear segment 17 are about to go into mesh with the teeth on the rack 11. Also, the teeth on the gear sector 18 have just become disengaged from the teeth 13 on the pendulous body 7. It follows therefore, that at this moment, the roller 26 comes into rolling contact with the cam 23. It is obvious too, that the cooperation of the elements 26 and 23 permits a continuous or unbroken change from the mesh of the sector teeth 18 and the teeth 13, and an intermesh of the teeth on the gear segment 17 and the rack 11. In other words, in this particular point in the operation of the device, the teeth 17 and 11 do not come immediately into mesh, as the teeth 18 are disengaged from the teeth 13. Conse-

quently the cam 23 and roller 26 serve as a holding device at this interval of time to permit a smooth change to be made.

Assuming then, that the power shaft is rotating in a direction from right to left, and that the upstroke on the rod 15 is about to begin, it will be seen that owing to the peculiar shape of the gear sector 18, an initial thrust is brought to bear upon the plate 8 at the point 27, and 28. In other words, the lug 20 engages the shoulder 28, and the lug 19 engages the shoulder 27 to produce the initial movement in a direction from right to left of the pendulous body.

With this motion of parts, it is evident that the relationship of the gear segment 17 and rack 11 is somewhat as indicated in Fig. 4, which is known as the intermediate position. At this time, the eccentric pin 14 has moved from a point close to the power shaft to a more remote point. Incidentally, the close relationship of the point 14 with the power shaft beginning at the stroke, is obviously advantageous.

Moving on from the intermediate position, the parts take the position shown in Fig. 5, wherein the pitman has reached its uppermost point in the upstroke. The last tooth on the gear segment 17 is leaving the corresponding tooth on the rack 11, until it clears this tooth and the gear segment takes the position shown in Fig. 1. This is the beginning of the return stroke. Again, the roller 26 comes into engagement with the cam 23 and provide for the change and to allow the gear sector 18 to come into mesh with the teeth 13.

With the construction shown and described, it is obvious that the upstroke of the pitman rod 15 is positive, slow, and such that full advantage is taken of the powerful leverage provided during this movement. It follows also, that the return stroke is very rapid. Consequently, as stated at the outset, I have provided a novel mechanical movement which is dependable for converting rotary motion into reciprocatory motion and such that it can be advantageously used in connection with air motors and windmills developing a small power, but capable of using this small power to the best advantage regardless of wind conditions.

Although the structure has been developed for use for providing a better transmission of power, from a windmill to a pump, it is plainly obvious that it may be used to equal advantage in association with other forms of machinery.

It is thought that by considering the description in connection with the drawings, a clear understanding of the construction and operation of parts will be had. Therefore, a more lengthy description is thought unnecessary.

While the preferred embodiment of the

invention has been specifically illustrated and described, it is to be understood that minor changes in the shape, size, and variation in distances of parts, may be resorted 5 to within the scope of the adjoined claims.

Having thus described my invention, what I claim as new is:—

1. In a mechanical movement of the class described, a fixedly mounted fulcrum, a pendulous body mounted for oscillation on said fulcrum, an eccentric pitman connecting pin carried by said body, a power shaft mounted for rotation in fixed relationship to said fulcrum, complemental gearing between said shaft and body for oscillating said body in opposite directions and for producing a relatively slow movement of the body in one direction and a relatively rapid movement of the body in an opposite direction, complemental elements carried by said body and shaft for producing a retention device adapted to come into play at the end of each stroke of the body to provide for a smooth change in the gearing.
2. In a mechanical movement of the class described, a stationary fulcrum, a segmental plate mounted for oscillation thereon, said plate being provided with a pitman rod co-acting pin eccentrically located, being provided with an enlarged opening having an arcuate toothed rack bar at one side and having a pair of gear teeth located on an opposite side, said gear teeth being disposed close to said fulcrum, a power shaft mounted for rotation and in fixed relationship to said fulcrum, a segmental gear fixedly mounted on said power shaft and located in said opening for cooperating with the teeth of said rack bar, a relatively small toothed gear sector also carried by said power shaft and superimposed upon the central portion of said gear segment for cooperation with said pair of gear teeth, said gear sector being provided with outstanding lugs for cooperation with end edges in the opening of said plate, an arm carried by said plate and spaced from and swingable about said fulcrum, said arm being provided on its free end with a cam, and an additional arm carried by said power shaft, and an antifriction roller mounted for free rotation in the extremity of said additional arm and located for cooperation with said cam.

toothed gear sector also carried by said power shaft and superimposed upon the central portion of said gear segment, for cooperation with said pair of gear teeth, said gear sector being provided with outstanding lugs for cooperation with end edges in the opening of said plate.

3. In a mechanical movement of the class described, a stationary fulcrum, a segmental plate mounted for oscillation thereon, said plate being provided with a pitman rod eccentrically located, being provided with an enlarged opening having an arcuate toothed rack bar at one side and having a pair of gear teeth located on an opposite side, said gear teeth being disposed close to said fulcrum, a power shaft mounted for rotation and in fixed relationship to said fulcrum, a segmental gear fixedly mounted on said power shaft and located in said opening for cooperating with the teeth of said rack bar, a relatively small toothed gear sector also carried by said power shaft and superimposed upon the central portion of said gear segment for cooperation with said pair of gear teeth, said gear sector being provided with outstanding lugs for cooperation with end edges in the opening of said plate, an arm carried by said plate and spaced from and swingable about said fulcrum, said arm being provided on its free end with a cam, and an additional arm carried by said power shaft, and an antifriction roller mounted for free rotation in the extremity of said additional arm and located for cooperation with said cam.

In testimony whereof I affix my signature.
EBENEZER D. HARRIS.
